Patented Apr. 25, 1922.

Martin L. Beistle ^{Inventor}
By his Attorney
Frank J. Kent

UNITED STATES PATENT OFFICE.

MARTIN L. BEISTLE, OF SHIPPENSBURG, PENNSYLVANIA.

TISSUE-PAPER ORNAMENT.

1,414,006.

Specification of Letters Patent. Patented Apr. 25, 1922.

Application filed October 24, 1919. Serial No. 333,040.

To all whom it may concern:

Be it known that I, MARTIN L. BEISTLE, a citizen of the United States, residing at Shippensburg, in the county of Cumberland and State of Pennsylvania, have invented certain new and useful Improvements in Tissue-Paper Ornaments, of which the following is a specification.

This invention relates to ornaments on the order of the folding paper bells which are used to a large extent for decorative purposes at Christmas time.

One of the principal objects of the invention is to so construct the ornament that in the simple act of unfolding and setting up the same, an appropriate hanger or support will be provided for suspending the ornament at its center.

Other objects are to simplify and cheapen the construction and to make the ornament more durable and lasting.

The foregoing objects have been attained by a special novel construction and arrangement of parts, an example of which is disclosed in the accompanying drawing.

In said drawing, Figure 1 is a side view of one of the so-called "Christmas bell" ornaments in its folded condition and Figure 2 is an edge view.

Figure 3 is a view of the same in its expanded or completed form.

The body of the ornament is made up of a plurality of superimposed leaves or layers, usually of paper and which in the present instance take the shape of half-bell sections.

These sections are secured together at their rear or inner edge, in the example illustrated, by fastenings or staples 6 passed through rearwardly projected tabs 7, said tabs being spaced apart, at the upper and lower portions of the bell. More of these spaced tabs may be provided in the larger size ornaments, but ordinarily two, such as indicated, will suffice.

On the outermost leaves there are secured, by pasting or otherwise, the backing or reinforcing strips 8, 9 which may be made, for instance, of cardboard or heavier paper. These backing strips may be made to conform generally to the outline of the leaves, as shown, and they are preferably located forwardly of the tabs 7. The rearward edge of these backing strips may be made straight as indicated at 10 to constitute in effect the hinge line on which the leaves will open.

At their upper ends the backing strips are provided with rearwardly directed lugs or extensions 11 and these lugs are formed with perforations 12 or other fastening means disposed substantially on the plane of the hinge line and consequently on the central axis of the ornament.

In use, the normally flat pad is opened up by rotating the backing strips 8, 9 toward each other until they are in back to back engagement. This opens up the leaves of the ornament and brings the perforations 12 in the supporting lugs into register at a point substantially in line with the axis of the bell, or other ornament. A suspending cord may then be passed through the registered openings to secure the parts in expanded relation and to provide a suspension means in line with the true axis of the ornament. With this arrangement, therefore, it is a simple matter to secure the ornament in its expanded condition and to suspend it so that it will hang straight. These rearwardly extending supporting lugs 11 also brace the relatively weaker pointed portions 13 at the upper ends of the leaves.

I claim:

1. A device of the kind described, comprising a plurality of connected superimposed leaves and backing strips secured to the outermost leaves, the leaves and strips having edge portions in a straight line and being rotatable about the straight line, one of the strips provided at one end with a supporting extension that projects on both sides of a plane which includes the straight line and which is perpendicular to the surface of the strip.

2. A device of the kind described, comprising a plurality of connected superimposed leaves and backing strips secured to the outermost leaves, the leaves and strips having edge portions in a straight line and being rotatable about the straight line, each of the strips provided at one end with an extension that projects on both sides of a plane which includes the straight line and which is perpendicular to the surface of the strip each extension provided with an aperture through which said plane passes.

In testimony whereof I affix my signature.

MARTIN L. BEISTLE.
